(57) **CLAIM**

The ornamental design for the footwear, as shown and described herein.

DESCRIPTION

FIG. 1 is an elevated, perspective view of my footwear in accordance with an embodiment of my invention;

FIG. 2 is a front view of the embodiment of FIG. 1;

FIG. 3 is a rear view of the footwear;

FIG. 4 is an inner side view of the footwear;

FIG. 5 is an outer side view of the footwear;

FIG. 6 is a top view of the footwear;

FIG. 7 is a bottom view of the footwear; and,

FIG. 8 is a bottom view of an alternate embodiment of the footwear, all other views of this embodiment being the same as the first embodiment.

The broken lines shown form no part of the claimed design.

1 Claim, 8 Drawing Sheets(56)
